DESIGN FOR A RIBBON

Thomas H. Kinney, Bally, Pa., assignor to The Bally Ribbon Mills, Inc., Bally, Pa., a corporation of Pennsylvania

Application March 28, 1939, Serial No. 83,869

Term of patent 3½ years

To all whom it may concern:

Be it known that I, Thomas H. Kinney, a citizen of the United States and a resident of Bally,
in the county of Berks and State of Pennsylvania,
have invented a new, original, and ornamental Design for a Ribbon, of which the following is a specification, reference being had to the accompanying drawing, forming part thereof.

The figure is a plan view of a ribbon embodying my design.

I claim:

The ornamental design for a ribbon as shown.

THOMAS H. KINNEY.
